(57) **CLAIM**

The ornamental design for a display screen or portion thereof with a graphical user interface, as shown and described.

DESCRIPTION

FIG. 1 is a front view of a first embodiment of a display screen or portion thereof with a graphical user interface.

FIG. 2 is a front view of a second embodiment of a display screen or portion thereof with a graphical user interface.

FIG. 3 is a front view of a third embodiment of a display screen or portion thereof with a graphical user interface.

FIG. 4 is a front view of a fourth embodiment of a display screen or portion thereof with a graphical user interface.

FIG. 5 is a front view of a fifth embodiment of a display screen or portion thereof with a graphical user interface.

FIG. 6 is a front view of a sixth embodiment of a display screen or portion thereof with a graphical user interface.

FIG. 7 is a front view of a seventh embodiment of a display screen or portion thereof with a graphical user interface.

FIG. 8 is a front view of an eighth embodiment of a display screen or portion thereof with a graphical user interface.

FIG. 9 is a front view of a ninth embodiment of a display screen or portion thereof with a graphical user interface.

FIG. 10 is a front view of a tenth embodiment of a display screen or portion thereof with a graphical user interface.

FIG. 11 is a front view of an eleventh embodiment of a display screen or portion thereof with a graphical user interface.

FIG. 12 is a front view of a twelfth embodiment of a display screen or portion thereof with a graphical user interface; and, FIG. 13 is a front view of a thirteenth embodiment of a display screen or portion thereof with a graphical user interface.

(Continued)

The broken lines showing a mobile device illustrate environmental structure and form no part of the claimed design. All other broken lines in the drawings depict portions of a graphical user interface that form no part of the claimed design.
